UNITED STATES PATENT OFFICE

JAMES K. SCOTT, OF EAST ORANGE, NEW JERSEY, ASSIGNOR TO AMERICAN THROTTLE COMPANY, INC., OF NEW YORK, N. Y.

THROTTLE

Application filed July 12, 1928. Serial No. 294,476.

This case is a continuation in part of United States application Serial Number 184,713 filed on April 18, 1927, and as to matter common to that case and the present one the filing date of the former is claimed for purposes of priority.

This invention relates to throttles for locomotives and has particular reference to throttles of the so-called multiple type, such as disclosed in United States Patent Reissue 16,285 granted to Ray M. Brown. The object of the present invention is to provide an improved means for balancing the individual valves so that they can be readily opened, at the same time leaving them unbalanced when they are closed so that they remain tight on their seats.

The invention is illustrated on the four sheets of drawings herewith in which Fig. 1 is a longitudinal central section of the front part of a locomotive with my invention applied; Fig. 2 is a composite view, the left half being a front elevation of the apparatus illustrated in Fig. 1, while the right half is a sectional view on line 2—2 of Fig. 1; Fig. 3 is an enlarged longitudinal sectional view of one of the valves; Fig. 4 is a top view of Fig. 1, portions of the smoke box and boiler shell as well as some other portions being broken away for the sake of clearness; Fig. 5 is a view similar to Fig. 3, illustrating a modification, and Fig. 6 a fragmentary sectional view on line 6—6 of Fig. 5.

The flue sheet of the boiler is shown at 1, the flues 2—2 extending backward from it. 3 is the boiler sheet while 4 is the smoke-box sheet. The stack is indicated at 5. The dry pipe appears at 6 while the steam pipes can be seen at 7—7. The superheater elements 8—8 extend in the ordinary way into the flues 2—2 and have their ends connected to the header 9. This header has a transverse chamber 9^a, with which the forwardly extending fingers 9^b communicate, and a second transverse chamber 12, with which the fingers 14, which are intermeshed with the fingers 9^b, communicate. Steam is delivered by the dry pipe 6 to the chamber 9^a of the header 9, flows from this chamber into the fingers 9^b and superheater elements 8, is returned by

them in a superheated state to the fingers 14 and space 12 of header 9, whence it flows through the pipes 7 to the steam chest of the locomotive. All of this is of the ordinary construction.

In the patent referred to above, the flow of the steam from the header is controlled by a transversely arranged series of relatively small throttles. This same general arrangement is shown in the present case. The throttles are shown at 10—10. They engage seats in the partition 11 which separates the space 12 from the space 13. Space 12 is in direct communication with the fingers 14 of the header into which the steam flows on leaving the superheater elements; while 13 is in direct communication with the steam pipes 7 by means of the connections 15. When all the throttles 10—10 are closed the steam flow from the boiler to the steam pipe 7 is therefore cut off.

The throttles are actuated by means of a transversely arranged shaft 16 which bears arms 17 each of which engage a stem 18 of a throttle. By this arrangement the throttles can be opened in any sequence desired, the arms 17 and the relative length of stems 18 being arranged so that the former come into contact with the lower ends of the latter in the desired sequence.

If no means are provided for at least partially balancing these valves, it will be rather difficult to open them even if they are made quite small.

My invention is concerned with a novel means of effecting such balancing.

Each of the valves 10 has a cylindrical portion 19 which reciprocates in a cylindrical recess 20 in a cap 21. The fit between the two is made rather loose. These caps are set into openings in the upper wall 22 of the header opposite the valves and in exact alignment with them, their primary purpose being to provide access for insertion and removal of the valves and for grinding the valve seats. The seats are preferably separate rings 11^a, pressed into the openings in partition 13. They are preferably equipped with spiders 11^b carrying guides 26, through which the stems 18 extend.

One of the valves, which is given the special reference numeral 10^a and which is illustrated on an enlarged scale in Fig. 3, is provided with a small pilot valve 23 and is of special construction for this purpose. It has no continuous stem 18 like the other valves. There is instead a separate cylindrical piece 24 which reciprocates in the guide 26 of the spider 11^b and has a shoulder 25 limiting its downward movement. When the valve 10^a is seated and the shoulder 25 is in engagement with the upper side of guide 26, there is a space 27 between the upper end of the piece 24 and the lower face of the valve 10^a. The stem 28 of the pilot valve extends axially through the valve 10^a and the piece 24. Its lower end extends below the lower end of the piece 24 when the head 29 of the pilot valve is seated on its seat 30 in the upper face of the valve 10^a. A plurality of passages 31 extend from the space 32 below the head of the pilot valve to the lower face of valve 10^a, thus putting the cylindrical space 20 into communication with the space 13 when the pilot valve is raised off its seat.

All of the spaces 20 in the caps 21 are put into communication with each other by means of a manifold 33, whose several outlets register with holes in the caps 21.

The operation of the device will now be readily understood. When all of the throttles are closed and the fingers 17 all out of contact with the valve stems, steam that has leaked past the cylindrical portions 19 into the spaces 20 causes these valves to be seated firmly on their seats. When the engineer now makes the first movement in opening the throttle, the arm 17 under the stem 28 of the pilot valve is the first to come into action. It raises the pilot valve 29 off its seat 30, thereby putting all of the spaces 20 into communication with the space 13 through the manifold 33 and the channels 31. The steam in the spaces 20 and in the manifold therefore promptly escapes and the valves are now substantially balanced. A further movement of the rod 16 in a counter-clockwise direction as viewed in the drawings raises the throttles 10, the order of opening being in accordance with the relative spacing of the arms 17 from the stems 18.

When the throttles are to be closed, a clockwise movement of the shaft 16 as viewed in Figs. 1 and 3 permits the throttles to come down successively on their seats. After the last one is seated a further movement permits the pilot valve to become seated and thereupon leakage past the cylindrical portions of the valves 10 will again build up pressure in the spaces 20 and in the manifold 33.

It will be seen that by the above arrangement I have provided a very simple and effective means for balancing all of the valves in such a multiple system. The modification according to Figs. 5 and 6 consists essentially

in substituting a cored channel or passage 33^a for the manifold 33, branches 33^b extending from this passage through the caps 21 to the spaces 20 inside of the caps. This channel with its branches provides communication between the several caps in the same way as the manifold in the form first described. Except for this change the second form is exactly like the first and its action will be obvious. This form is preferable to the one first described inasmuch as access to the caps is not blocked. Moreover, in practice it is rather difficult to make tight joints simultaneously between all the branches of the manifold of the first form and the several caps. 75

I claim:

1. In apparatus of the class described, the combination of an elongated chamber; a longitudinal partition dividing it into two spaces and provided with an alined series of apertures; a series of removable caps in the outer wall of one of the spaces, each having a cylindrical hollow portion alined with one of said apertures; a series of valves each adapted to close one of said apertures and having a cylindrical portion reciprocating in one of said hollows of the caps; a duct placing all of the hollow cap spaces into communication with each other; and means comprising a relatively small pilot valve to release pressure 95 from the cap hollows.

2. In apparatus of the class described, the combination of an elongated chamber, a longitudinal partition dividing it into two spaces and provided with an alined series of apertures; a series of removable caps in the outer wall of one of the spaces, each having a cylindrical hollow portion alined with one of said apertures; a series of valves each adapted to close one of said apertures and having a cylindrical portion reciprocating in one of said hollows of the caps; a duct having a plurality of branches, each branch opening into one of the cylindrical hollow spaces; and a relatively small pilot valve which, when opened, puts the cap hollows and the second space into communication. 100

3. In apparatus of the class described, the combination of an elongated horizontal chamber, a partition dividing it into upper and lower spaces; said partition being provided with a series of alined apertures; a series of removable caps in the outer wall above the apertures each having a hollow cylindrical interior alined with an aperture; a series of valves each adapted to close one of said apertures and having a cylindrical portion reciprocating in the associated hollow cap; there being a channel in the wall of said chamber adjacent to said caps, with branches extending to the interiors of the caps; and a pilot valve associated with one of said valves which when opened puts the corresponding cap hollow, and through the said channel and 115 120 125 130

branches all the other cap hollows, into communication with the lower space.

4. In apparatus of the class described, the combination of an elongated horizontal chamber; a partition dividing it into upper and lower spaces; said partition being provided with a series of aligned apertures; a series of removable caps in the outer wall above the apertures each having a hollow cylindrical interior aligned with an aperture; a series of valves each adapted to close one of said apertures and having a cylindrical portion reciprocating in the associated hollow cap; there being a channel in the wall of said chamber adjacent to said caps, with branches extending to the interiors of the caps; a downwardly extending portion associated with each valve; operating means to open said valves by acting on said portions, the arrangement being such that some of the valves open later than others; one of said valves having a passage from its upper to its lower side; a pilot valve controlling said passage; and means to open said pilot valve before any of the other valves are opened.
